(57) **CLAIM**

The ornamental design for a mirror as shown and described.

DESCRIPTION

FIG. 1 is a front perspective view of the mirror of the present invention;

FIG. 2 is a front elevational view of the mirror shown in FIG. 1;

FIG. 3 is a rear elevational view of the mirror shown in FIG. 1;

FIG. 4 is a left side elevational view of the mirror shown in FIG. 1;

FIG. 5 is a right side elevational view of the mirror shown in FIG. 1;

FIG. 6 is a top view of the mirror shown in FIG. 1; and, FIG. 7 is a bottom view of the mirror shown in FIG. 1.

The drawings illustrate a mirror, as shown in the drawings. Contour lines are included in the various views of FIGS. 1 through 7 to depict surface curvature, flatness and/or other shapes, e.g., reflectiveness. Illustrative portions that are depicted in broken lines form no part of the claimed design.
